UNITED STATES PATENT OFFICE.

JAMES A. HORTON, OF BROOKLYN, NEW YORK, ASSIGNOR TO IROQUOIS MACHINE COMPANY, OF NEW YORK, N. Y., A CORPORATION OF NEW YORK.

SWAGING-MACHINE.

No. 835,729.

Specification of Letters Patent.

Patented Nov. 13, 1906.

Application filed July 27, 1901. Renewed April 16, 1902. Serial No. 103,187.

To all whom it may concern:

Be it known that I, JAMES A. HORTON, of Brooklyn, in the county of Kings and State of New York, have invented certain new and 5 useful Improvements in Swaging-Machines, of which the following is a specification.

This invention relates to metal-swaging machines employing a die-holder having dies to act on the work and a roll-cage having 10 rolls which transmit radial blows through the dies to the work when the roll-cage and die-holder receive a relative rotary movement.

Heretofore the roll-cage has rotated loosely, being moved intermittently by the die-holder 15 at each blow, which has caused great racking strains, resulting in noise and rapid deterioration of the machine.

One of the objects of my invention is to reduce the noise and wear and preserve a 20 definite ratio of rotation between the die-holder and the roll-cage.

Another object is to enlarge the capabilities of the machine, and this I accomplish by imparting a progressive inward movement to 25 the dies upon the work and making them adjustable as to the opening between them, all in a novel manner as hereinafter described and claimed.

Of the accompanying drawings, forming a 30 part of this specification, Figure 1 represents a side elevation of a swaging-machine constructed in accordance with my invention, partly broken away and in section. Fig. 2 represents a front elevation partly broken 35 away. Fig. 3 represents a vertical longitudinal section. Fig. 4 represents a section on line 4-4 of Fig. 3. Fig. 5 represents a perspective view of the die-holder. Fig. 6 represents a side elevation of the hammering device. Fig. 7 represents a perspective view of the props and their carrier. Fig. 8 represents a side elevation, partly in section, showing one of the die-blocks and the corresponding prop. Fig. 9 represents an end elevation 45 of the die-holder with contents removed. Fig. 10 represents a perspective view of the prop-controlling cam. Fig. 11 represents a rear elevation of said cam. Fig. 12 represents a view similar to Fig. 8, showing a modified form of prop and die.

The same reference characters indicate the same parts in all of the figures.

In the drawings, 1 is a rotary hollow shaft having a belt-wheel 2 and carrying at its forward end a cylindrical die-holder 3, provided with diametric slots or guides 4, in which are mounted the opposed die-blocks 5 and their backers 6. A pair of props 7, hereinafter described, are interposed between the die-blocks and backers.

8 is a fixed annular holder held in the machine-frame 9 and within the hub of which the shaft 1 rotates, said holder having a fixed steel ring 10, which forms the outer bearing for a series of rolls 11, mounted in sockets 65 in a roller-cage 12. The backers 6 are provided with rounded outer ends which project slightly into the path of the rollers 11, with the result that as the die-holder 3 is rotated within the circle of rolls 11 the latter engage and force inwardly the backers 6, acting as hammers whose impact is transmitted in a radial direction through said backers and the props 7 to the die-blocks 5, so that the two die-blocks are forced together with a hammering action upon the work which is inserted 70 between them. The periphery or hub of the roller-cage 12 is provided with gear-teeth 13, meshing with a small gear 14 upon a counter-shaft 15, which has fixed to it a gear 16, 75 meshing with a gear 17, fixed to the shaft 1. By this means the roll-cage 12 is positively rotated in the same direction as the die-carrier 3, but at a slower speed, which is made equivalent to the speed which would be imparted to said roll-cage at the moment of engagement between the backers 6 and any pair of rolls if the roll-cage were allowed to rotate 80 loosely. By thus positively controlling the relative rate of rotation of the die-holder and 85 series of rolls I am enabled to avoid the excessive racking to which machines employing a loosely or idly rotating roll-holder are subject, such racking arising from the fact that each time the backers strike a pair of 90 rolls the speed of the whole series of rolls, which falls between the blows, must be suddenly and momentarily accelerated. The shock thus produced causes great noise and 95 wear, which are largely done away with in my machine. By positively controlling the relative rate of rotation of the roll-cage and the holder I am also enabled to impart different angular cross-sections to the work by

using dies which have flat or tangent working faces and rotating the work at a proper speed.

18 is a retaining-plate removably secured 5 to the face of the die-holder 3 and having apertures through which the ends of the props 7 project, and 19 is an outer retaining-plate secured to the face of the fixed holder 8, said plates having central apertures through 10 which the work may be inserted between the dies.

The two props 7 are of tapered form, being provided with outer or back sides 20 parallel to the axis of the shaft 1 and fitting 15 against the complementary inner sides of the backers 6 and with inner sides 21, having a general inclination to the said back sides and fitting against complementary-inclined back sides 22, formed on the die-blocks 5. By 20 imparting an axial movement to the props 7 between the backers and die-blocks the distance between the working faces of said die-blocks and the outer ends of the backers 6 may be varied, and since the rollers 11 have 25 a fixed range of movement under the constraint of the ring 10 such movement of the props will have the effect of varying the size of the aperture between the die-blocks.

For the purposes of the present specification and claims I consider the die or swaging-tool as that immediate portion of the die-block 5 upon which its working face is formed, while the outer portion of said die-block on which the inclined face 22 is 35 formed constitutes part of an abutment of variable width interposed between the die and the hammering device, the other parts of said abutment being the props 7 and backers 6. The axial movement of the props 7, 40 therefore, has the effect of increasing or decreasing the width of this abutment. An automatic advance of the props 7 during the operation of the hammering device, whereby the dies are gradually closed up on the work, 45 is secured as follows: The props 7 are affixed to a head or carrier 23 by means of pins 24 24 on the carrier occupying holes 25 25, formed in the props, whereby the props are held to the carrier as respects axial movement, but 50 are adapted to move to a limited extent radially with respect thereto. The carrier 23 is attached to a stem or rod 26, mounted to slide in the central aperture of the hollow shaft 1, and is yieldingly projected forwardly 55 in a direction to advance the props by a spring 270. The said prop-advancing movement of the rod 26 is resisted by a crown-cam 27, loosely surrounding the shaft 1 and having its hub formed with a gear 28, which meshes 60 with a gear 29, fixed to the counter-shaft 15. The gears 17 and 28 have the same number of teeth, and the gear 29 has one more tooth than the gear 16, so that the cam 27 performs a one rotation relatively to the shaft 1 in a 65 large number of rotations of said shaft. The

working edge of the cam 27 is provided with a series of steps 290 290 and is engaged by a pin 30, attached to the rod 26 and projecting through an axially-elongated slot 31 in the shaft 1.

In Fig. 10 the pin 30 is shown resting 70 against the first or left-hand-most step 290, which will withdraw the props 7 to their greatest extent toward the left. As the cam 27 revolves around the shaft 1 the pin 30 75 passes in succession on to the steps of the cam and permits the spring 270 to slowly advance the props 7 toward the right in a step-by-step manner, thereby gradually closing up the space between the dies. An incline 32 on the cam 27 leads from the last 80 step in the series to the first step, so that the cycle of the cam may be continuously repeated. The rear end of the rod 26 is exposed beyond the rear end of the shaft 1 and is provided with a knob or handle 33, whereby the rod and wedges may at any time be retracted 85 by hand.

I form the inclined faces of the props 7 7 and die-blocks 5 5 into a series of steps or serrations 34 35, having individual coacting 90 faces 36 37 parallel to the axis of the shaft 1, and with inclined or rounded faces 38 39 on their corners, which rounded faces exert a cam-like action against each other during the 95 advance of the props from one step to another, whereby the props are permitted to travel upon the die-blocks easily during periods between blows. Centrifugal force acts to throw the props, backers, and die-blocks outwardly between blows, so that the 100 advance of the props is easily effected. The pressure of the blows is transmitted at right angles to the parallel faces of the steps on the props and die-blocks, so that there is no cam 105 action, as in the case of a wedge, tending to retreat the props. The props are advanced by each step of the cam 27 a distance equal to the length of one of the steps 34 35.

To limit the outward radial movement of 110 the backers 6 6 under the influence of centrifugal force and prevent them from striking with too great an impact against the rolls 11 or their holder, I form the backers 6 with retaining-lips 47 47, fitting within grooves or 115 pockets 48 48 in the die-holder 12.

In Fig. 12 I show a modification of my invention in which wedges 44, having straight inclined sides 45 coacting with complementary sides 46 on the die-blocks 5, are employed in place of the serrated props 7. In 120 this case the wedges are preferably advanced positively instead of by means of a spring.

By means of my improved swaging-machine I am enabled to impart shapes to the work which cannot be imparted by any prior swaging-machines of which I have knowledge. One such shape or conformation is 125 that which the work 40 is represented as hav- 130

ing in Fig. 3—namely, an enlarged body or stem 41, a reduced neck 42, and a head or outer portion 43 of larger diameter than said neck.

5 I do not confine myself to the exact construction herein set forth, as considerable variation may be made without departing from the spirit of my invention.

I claim—

10 1. In a swaging-machine, a hammering device and a swaging-die mounted and geared for positive relative concentric movement, and an abutment of variable width interposed between the two.

15 2. In a swaging-machine, a hammering device and a swaging-die mounted and geared for positive relative concentric movement, an abutment of variable width interposed between the two, and means to automatically 20 and progressively vary the width of said abutment.

25 3. In a swaging-machine, a hammering device and a swaging-die mounted and geared for positive relative concentric movement, and a tapering prop interposed between said hammering device and die.

30 4. In a swaging-machine, a hammering device and a swaging-die mounted for relative concentric movement, and a serrated tapering prop interposed between the hammering device and die.

35 5. In a swaging-machine, a hammering device and a swaging-die mounted and geared for positive relative concentric movement, the die being movable radially of the axis of rotation, and a tapered prop interposed between the hammering device and die and movable longitudinally of said axis.

40 6. In a swaging-machine, a hammering device and a swaging-die mounted for relative concentric movement, the die being movable radially of the axis of rotation, a tapered prop interposed between the hammering device and die and movable longitudinally of said axis, said prop having steps provided with acting faces parallel to its direction of movement, and a coacting radially-movable member interposed between the hammering device and die and having complementary 45 steps.

50 7. In a swaging-machine, a hammering device and a swaging-die mounted for relative concentric movement, the die being movable radially of the axis of rotation, a tapered prop interposed between the hammering device and die and movable longitudinally of said axis, said prop having steps provided with acting faces parallel to its direction of movement, a coacting radially-movable 55 member interposed between the hammering device and die and having complementary 60

steps, and automatic means to intermittently advance said prop.

8. In a swaging-machine, a hammering device and a swaging-die mounted for relative 65 rotation, the die being movable radially of the axis of rotation, a tapered prop interposed between the hammering device and die and movable longitudinally of said axis, said prop having steps provided with acting faces 70 parallel to its direction of movement, and a coacting radially-movable member interposed between the hammering device and die and having complementary steps, the corners of the steps on the prop and complementary 75 member having coacting cam-inclines.

9. In a swaging-machine, a hammering device and a die-holder mounted and geared for positive relative concentric movement, said die-holder having diametric guides, opposed die-blocks and their backers mounted for radial movement in said guides, an axially-movable prop-carrier, and a pair of tapered props interposed between the die-blocks and backers, said props being held to 85 their carrier as to axial movement and radially movable with respect thereto.

10. In a swaging-machine, a hammering device and a die-holder mounted for relative concentric movement, die-blocks and their 90 backers movable radially on said die-holder, props interposed between said die-blocks and backers and movable longitudinally of the axis of rotation, a carrier for said props having an externally-exposed handle, a spring 95 adapted to move said carrier in a prop-advancing direction, and a cam mounted to rotate with respect to the die-holder and opposing said spring.

11. In a swaging-machine, a hammering 100 device and a die-holder mounted and geared for positive relative concentric movement, a swaging-die and backer mounted for radial movement on said holder and coacting means on the backer and die-holder to limit the outward radial movement of said backer, said means consisting of ribs or lips on opposite sides of the backer, and recesses in the die-holder to receive said lips.

12. In a swaging-machine, a die-holder 110 having radially-movable die, a series of rolls adapted to impart hammering blows to said die, and means to produce a predetermined positively-controlled relative concentric movement of the die-holder and rolls.

115 In testimony whereof I have affixed my signature in presence of two witnesses.

JAMES A. HORTON.
